LEWIS FERRY MOODY, OF PHILADELPHIA, PENNSYLVANIA.

HYDRAULIC MACHINE.

Application filed September 18, 1924. Serial No. 738,389.

This invention relates to hydraulic apparatus such as hydraulic pumps or turbines and particularly to vertical shaft machines having a rotor of the unshrouded axial or 5 diagonal flow type. The general object of the invention is to provide such a machine of simple and efficient form and having a diffuser adapted to accommodate the whirling outflow from the rotor and to guide it out 10 along a simple expanding path.

Other objects of the invention, especially in the setting of the machine and the formation of a station sub-structure to contain the water passages will appear in the following 15 specification taken in connection with the accompanying drawings in which

Fig. 1 is a vertical sectional view of one embodiment of the invention in a pump installation and

Fig. 2 is a section taken on the line 2—2 of Fig. 1.

In the specific embodiment of the invention shown in the drawings a motor M on the pump station floor drives a pump rotor R by 25 shaft S extending down through the pit P. The pump receives its supply from the lower level t or the tail water basin through the intake passage 7 and vertical intake chamber 8 which is of general circular formation co- 30 axial with the pump rotor. This intake chamber 8 slightly contracts and then begins to diverge slightly in advance of the runner R. The walls of the intake thus merge gradually into a spreading discharge diffuser 10 35 receiving the discharge from the rotor and passing it on expanding lines to the spiral diffuser or chamber 11 and discharge outlet 12, the baffle 13 intervening between the outlet 12 and the spreading and spiral diffusers 40 as shown. The passages 7, 8, 10, 11 and 12 are preferably formed in the pump station sub-structure with pier structures 14 intervening between successive intake passages 7 of a series and piers 15 interposed at the 45 middle of each of said passages. Similarly pier members 16 intervene between successive outlets 12 giving a very strong construction.

The impeller R is of the diagonal outward flow type having a greater radial than axial 50 extent and the pit P between the impeller head cover and station floor gives access to the movable parts. The intake passage 7 is

of the double spiral type leading the water from each portion to the inlet chamber 8. In this chamber 8 the flow passes upward to the 55 rotor R and is discharged diagonally outward into the spreading diffuser 10 with a large component of whirl around the impeller axis. In this diffuser the discharge is free to expand along spiral lines with continuous 60 increase in cross section so that all components of the flow are evenly decelerated and their velocity head reconverted into pressure head. By the time the flow reaches the spiral diffuser 11 its velocity is considerably reduced 65 and in this diffuser the flow lines are gathered into a stream progressing along expanding volute lines to the discharge outlet 12. The spreading diffuser 10 may discharge either 70 into a spiral diffuser or merely a simplified form of chamber having a circular end wall. The end of the intake 7 may also be circular; both intake and discharge passages may be made to approximate spirals by making them eccentric.

Guide vanes V in the inlet chambers are inclined to give a whirl to the entering flow. The crest C between the spreading and spiral diffusers is at a higher elevation than the discharge or head water level h of the head water 80 basin and the spiral diffuser 11 and outlet 12 are inclined downward in the direction of discharge to empty below the level h. The discharge passages are thus siphonic so that the impeller spaces may be emptied and the impeller removed without the use of gates in the discharge. It also becomes possible by this arrangement to start the pump at low torque by first running the impeller in air and then 85 priming it after starting by removing the air from the passage through the use of an ejector diagrammatically shown at 17. This method of starting is sometimes desirable when certain types of motor are used for driving the pump.

By this invention the necessity of providing gates or valves is entirely eliminated; an efficient diffuser 10 is provided and the rotor R is freely accessible for inspection when the unit is shut down. The position of the rotor R 100 between the head water and tail water levels permits the rotor to be placed to most advantageously regulate the pressures in the inlet and diffuser, and where the rotor is up near

head water as shown in the drawings, the overall height of the machine is reduced with corresponding saving in expense.

I claim:

- 5 1. In a hydraulic machine, a rotor, a passage formed by a circular wall extending above and below said rotor thereby providing an entrance and discharge therefor, the discharge side of said passage having a portion 70 relatively gradually enlarging in the direction of fluid flow therethrough thereby to decelerate the fluid flowing away from the rotor, said rotor being located in the upper portion of said passage, means forming a sealed chamber extending below and on the outside of the upper end of said wall, a liquid basin communicating with said chamber entirely below the top of said wall, and a liquid basin below 75 said rotor and extending above the lower end 80 of said wall.
- 15 2. In a hydraulic machine, a rotor, a passage formed by a circular wall forming a conduit extending above and below said rotor thereby providing an entrance and discharge 85 therefor, the entrance side of said passage having a portion relatively gradually decreasing in cross-sectional area in the direction of fluid flow therethrough, thereby to accelerate the fluid flowing toward said rotor, said rotor 90 being located in the upper portion of said passage, means forming a sealed chamber located above and extending below and on the outside of the upper extremity of said conduit, a liquid basin communicating with said 95 chamber entirely below the upper extremity of said conduit, and a liquid basin below said rotor and sealing the lower extremity of said conduit.
- 20 3. In a hydraulic machine, a rotor having a vertical axis of rotation, a passage formed by a circular wall forming a vertical conduit extending above and below said rotor, said rotor being located in the upper portion of said passage, the portion of said conduit on 100 one side of said rotor forming a decelerating passage, means forming a sealed chamber above said wall and extending below and on the outside of the exterior of the upper end of said conduit, a liquid basin communicating 105 with said chamber entirely below the top of said wall, and a liquid basin below said rotor and sealing the lower end of said conduit.
- 25 4. In a hydraulic machine, a pair of liquid basins having different elevations, means forming a vertical circular conduit extending entirely above the upper basin and below the level in the lower basin, an axial flow rotor located in the upper portion of said conduit 110 between the liquid levels of said basins and an ejector for removing air from said conduit.
- 30 5. In a hydraulic machine, a rotor, means forming a liquid chamber surrounding the axis of said rotor at the level of said rotor, 115 means forming a coaxial inlet passage communicating with said rotor, said passage extending entirely above the liquid in said basin and said rotor being disposed in the upper portion of said passage, and means for decelerating the flow of liquid discharged from 120 said rotor.
- 35 6. In a hydraulic pump, a rotor, a continuous wall forming a conduit extending above the lower portion of and surrounding said 125 rotor to form a discharge passage, means forming a liquid sealed chamber above said wall, an upper liquid basin communicating with said chamber entirely below the top of said wall and a liquid basin communicating with the lower end of said conduit, said rotor being disposed nearer the upper of said basins than the lower one.
- 40 7. In a hydraulic machine, a rotor having a vertical axis of rotation, a wall completely 130 surrounding said axis and forming a conduit communicating with the top of said rotor, means forming a sealed chamber extending laterally in substantially all directions from said wall while a portion of said chamber is continued in a lateral direction, and a liquid basin communicating with said chamber through said lateral continuation at the exterior entirely below the top of said wall and a liquid basin communicating with the lower end of said conduit, said rotor being disposed nearer the upper of said basins than the lower one.
- 45 8. In a hydraulic machine, a rotor having a greater radial than axial extent and being disposed between head water and tail water levels and having a vertical axis of rotation, said rotor being disposed adjacent the upper one of said levels, an annular wall completely 135 surrounding said axis and extending upwardly from the lower portion of said rotor, said wall forming a conduit communicating with the top of said rotor, means forming a sealed conduit directed toward the axis of said rotor above the top of said wall, and a liquid basin communicating with said sealed conduit entirely below the top of the exterior of said wall.
- 50 9. In a hydraulic machine, a rotor between head water and tail water and disposed nearer 140 the head water level than the tail water level and having a vertical axis of rotation, a circular wall completely surrounding said axis and extending upwardly from the lower portion of said rotor, said wall forming a conduit directed along the axis of said rotor, means forming a sealed annular conduit directed 145 toward the axis of said rotor and extending downwardly beyond the periphery of said wall, and a liquid basin communicating with said downwardly extending conduit portion entirely below the top of said wall.
- 55 10. In a hydraulic machine, a pair of liquid basins having different elevations, means forming a sealed conduit having its one end 150

- immersed in the liquid of the lower of said basins and having its upper end located entirely above the liquid level in the upper of said basins, a rotor in said conduit and located between the liquid levels in said basins, and nearer the upper one of said levels than the lower one thereof, and means for removing air from said conduit to establish a flow of liquid through said rotor.
11. In a hydraulic machine, a rotor having a vertical axis of rotation, means forming an open vertical upward flow decelerating conduit within which said rotor is located, a liquid basin communicating with the upper end of said conduit and the wall of said conduit forming a continuous crest extending above the level of the liquid in said basin to permit drainage of liquid from said conduit without permitting flow of liquid from said basin into said conduit, said rotor being disposed in a plane near the level of said basin.
12. In a hydraulic machine, a rotor between head water and tail water levels and having a vertical axis of rotation, means forming an open vertical flow decelerating conduit within which said rotor is located in the uppermost portion thereof, and means forming a liquid basin in which the liquid level is maintained below the top opening of said conduit.
13. In a hydraulic pump, a vertical upward flow rotor between head water and tail water levels and having a vertical axis of rotation, and means forming a conduit surrounding said axis above said rotor which is disposed in the uppermost portion of said conduit, said conduit being formed to decelerate liquid delivered from said rotor, and a liquid basin entirely below the upper extremity of said conduit but communicable with said conduit extremity by siphon action during operation of said rotor.
14. In a hydraulic machine, means forming head and tail water basins, a rotor between the head water and tail water levels and having a vertical axis of rotation, means forming a liquid chamber surrounding said axis above said rotor and discharging into said head water basin, and means forming a flow decelerating conduit of relatively short vertical dimension extending entirely above the level of the liquid in said basin and adapted to gradually decelerate the liquid delivered from said rotor to said chamber.
15. In a hydraulic pump, the combination comprising means forming a vertical flow passage, a vertical shaft carrying a runner of greater radial than axial extent, said runner being disposed within said passage adjacent its uppermost end, means forming a basin, and means communicating with said basin and forming therewith a liquid seal for said upper end which extends above the liquid level in said basin.
16. In a hydraulic pump, the combination comprising means forming a vertical upward flow passage, a vertical shaft carrying a runner disposed within said passage adjacent its uppermost end, said passage having portions adapted to accelerate and decelerate the fluid flowing respectively to and from said runner, means forming a liquid basin, and a closed passage extending downwardly from the upper end of said passage and having communication with said basin at a point below the level of said upper end.
17. In a hydraulic machine, the combination comprising means forming a vertical upward flow passage, the upper end of said passage having its cross sectional area gradually increased in the direction of flow therethrough, a vertical shaft carrying a runner the diameter of which is twice its axial extent, said runner being disposed within said passage adjacent its uppermost end, means forming a basin, and means communicating with said basin and forming a liquid seal for said upper end which extends above the liquid level in said basin.
18. In a hydraulic machine, the combination comprising means forming a vertical upward flow passage having a flaring upper end, the surface of which is formed as a surface of revolution, a vertical shaft carrying a runner disposed within said passage adjacent the uppermost end thereof, and means including a basin forming a liquid seal for said upper end which extends above the liquid level in said basin.
19. In a hydraulic machine, the combination comprising means forming a vertical flow passage having a flaring upper end, the surface of which is formed as a surface of revolution, a vertical shaft carrying a runner disposed within the flaring portion of said passage, and means including a basin forming a liquid seal for said upper end which extends above the liquid level in said basin.
20. In a hydraulic machine, the combination comprising means forming a vertical flow passage, means forming a closed space extending around the axis of said passage at the upper end thereof, said space having upper and lower surfaces diverging along a circular path concentric to the axis of the vertical passages, and a vertical shaft carrying a runner disposed within said vertical passage.
21. In a hydraulic machine, the combination comprising a vertical shaft carrying a runner, means forming a vertical flow passage having a portion of uniform cross-section which comprises an inflow passage to said runner and having provision at its lower and upper ends for varying the velocity of flow, means forming a basin, and a passage leading from said uppermost end and having communication with said basin at a point below the level of said upper end.
22. In a hydraulic machine, the combination comprising means forming a vertical flow passage having a straight vertical por-

tion, one end of said passage having provision for effecting both acceleration and deceleration of the flow, the other end of said passage also having provision for accelerating 5 the inflow, and a shaft carrying a runner disposed within the passage and between said acceleration and deceleration portions which are both disposed at the same end.

23. In a hydraulic machine, the combination comprising means forming a vertical 10 flow passage having a portion provided with a straight vertical wall, said passage having at one end thereof and on one side of said straight portion both gradually enlarging 15 and contracting cross-sectional areas thereby to effect acceleration and deceleration of the flow, and, said vertical passage also having provision at its other end to vary the velocity of the fluid flow relative to said vertical portion, and a shaft carrying a runner disposed 20 within said passage and between said enlarging and contracting cross-section areas.

24. In a hydraulic machine, a rotor, and means forming a flow decelerating conduit 25 within which said rotor is located between head water and tail water levels and is disposed nearer the head water level than the tail water level, the upper extremity of said conduit being located entirely above the normal 30 level of the head water communicating therewith during operation of said rotor.

25. In a hydraulic machine, a rotor between head water and tail water levels disposed nearer the head water level than the tail 35 water level, means forming a flow decelerating conduit rising vertically from said rotor, and means forming a passage descending from the upper extremity of said conduit toward the head water level.

40 26. In a hydraulic machine, a rotor, means forming a circular inlet passage for directing only an axial flow to said rotor, means adapted to impart whirl to the flow to said rotor, means forming a flow decelerating conduit 45 communicating with the opposite side of said rotor, and means forming liquid basins communicating with said passage and with said conduit respectively, the upper end of said conduit being located entirely above 50 the level of the liquid in the upper of said basins and forming an annular continuous

crest while said rotor is disposed nearer the upper of said basins than the lower one.

27. In a hydraulic machine, a rotor having a vertical axis of rotation, a wall completely 55 surrounding said axis and extending above the lower portion of said rotor to form a conduit communicating with said rotor which is disposed nearer the top of said conduit than the bottom, means forming a liquid 60 sealed chamber above said wall, a liquid basin communicating with said chamber and extending below the level of said rotor, and means for removing air from said chamber.

28. In a hydraulic machine, the combination comprising a vertical shaft rotor, a conduit in which said rotor is disposed, an upper 65 passage surrounding said shaft above said rotor to receive discharge therefrom, a diffuser passage adapted to receive and gradually decelerate the outflow from said upper passage, said upper and diffuser passages being of relatively short vertical dimensions.

29. In a hydraulic machine the combination 70 with a vertical shaft rotor, means forming upper and lower basins, and means forming a conduit allowing communication between said basins including a discharge diffuser therefor having a crest above the level 75 of the water in said upper basin, a closed passage between said upper basin and diffuser whereby there is formed a siphon permitting the rotor passages to be emptied without shutting off the discharge passages, the vertical dimension of said conduit above said 80 rotor being relatively small in comparison to that portion of the conduit below said rotor.

30. In a hydraulic machine the combination 85 with a vertical shaft rotor, means forming upper and lower basins, of means forming a conduit allowing communication between said basins including a diffuser receiving the discharge from said rotor and a downwardly inclined outflow passage receiving the flow 90 from said diffuser and leading it to a level below the top of the lower wall of said diffuser, the vertical dimension of said conduit above said rotor being relatively small in comparison to that portion of the conduit below said 95 rotor.
